[57] CLAIM

The ornamental design for a combined radio and television receiver, as shown and described.

DESCRIPTION

FIG. 1 is a front, top and right side perspective view of a combined radio and television receiver showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof;

FIG. 7 is a view similar to FIG. 1 with the television display face in retracted position; and

FIG. 8 is a rear, bottom and left side perspective view thereof, in display tube retracted position.
